F. L. GEORGE,
ACTION FOR UPRIGHT PIANOS.
APPLICATION FILED SEPT. 9, 1919.

Patented Dec. 14, 1920.

FIG. I.

INVENTOR.

FRANK L. GEORGE

UNITED STATES PATENT OFFICE.

FRANK L. GEORGE, OF LOS ANGELES, CALIFORNIA.

ACTION FOR UPRIGHT PIANOS.

1,362,414.

Specification of Letters Patent. Patented Dec. 14, 1920.

Application filed September 9, 1919. Serial No. 322,726.

To all whom it may concern:

Be it known that I, FRANK L. GEORGE, a citizen of the United States, residing at Los Angeles, in the county of Los Angeles and State of California, have invented new and useful Improvements in Actions for Upright Pianos, of which the following is a specification.

My invention relates to actions for upright pianos and consists of the novel features herein shown, described and claimed. This invention has for its object, among other things, principally to promote simplicity; to secure absolute repetition under any and all conditions; to reduce friction to the minimum; to secure ease and perfection of regulation; to obtain permanency of regulation; to obviate blocking of hammers under any and all conditions; to promote flexibility of parts and impart buoyancy to the touch; to provide ease or facility in removing any part while the action remains permanently in the piano; to effectually eliminate the many troublesome features existing in all other forms of upright actions now generally in use; to secure great saving of space occupied from front to rear of action; and to effect great saving of labor and material in manufacturing, installing and regulating.

It is another object of my invention to reduce the sudden shock of the blow from the key on the end of the abstract to practically eliminate the friction between the end of the key and the abstract, and to provide a means to facilitate the regulation of the action between the end of the abstract and the key, also to promote permanency of regulation.

Figure 1 is a side elevation of an action for upright pianos embodying the principles of my invention, the supporting parts being shown in cross section.

Fig. 2 is an enlarged fragmentary detail in elevation similar to Fig. 1 with parts omitted.

Fig. 3 is a detail view on an enlarged scale showing the construction and action of the capstan screw at the forward end of the forward swing, whereby the abstract is regulated in relation to the key.

In comparison with the standard upright piano action heretofore in use, I omit the back check wire, the tape and bridle wire, the wippen, and parts that go along with these elements.

The key-frame 1, the balance rail 2, and the key 3 may be of the usual construction. The rear end of the key 3 normally rests upon a felt 4 secured to the key-frame 1. 60

An action bracket 5 has an abutment 6 extending backwardly from its lower end. A felt 7 is mounted upon the abutment 6. The adjusting screw 8 is screw-seated in the lower flange rail 9 and the head of the screw rests upon the felt 7. A second abutment 10 extends from the bracket 5, and an expansive coil spring 11 is inserted between the second abutment 10 and the lower flange rail 9. The flange 12 is rigidly connected 70 to the lower flange rail 9 by a screw 13 and extends downwardly. The lower swing 14 is connected to the lower end of the flange 12 by a pin 15 and extends in a horizontal position forwardly to a plane above the rear end of the key 3. The abstract 16 is connected to the forward end of the swing 14 by a pin 17 and the abstract is nearly vertical. An arm 18 extends forwardly from the forward end of the swing 14 in 75 a higher plane. An adjusting screw 19 is tapped downwardly through the arm 18 and screws into a head 20 having a felt 21 bearing upon the key 3.

The intermediate action rail 22 is rigidly 85 mounted upon the bracket 5. The intermediate flange 23 is fixed upon the action rail 22 by a screw 24 and the upper swing 25 is connected to the flange 23 by a pin 26 and the upper swing 25 is connected to the abstract 16 by a pin 27. The upper end 28 of the abstract 16 is offset backwardly above the pin 27.

A rigid arm 29 extends from the action bracket 5. A swinging arm 30 is connected 95 to the forward end of the rigid arm 29 by a pin 31. There is a swinging arm 30 at each end of the lower flange rail 9 so as to hold the action rail in place between the adjusting screws 8 and the springs 11. The upper swing 25 takes the place of the usual wippen with all its complicated and trouble producing parts.

The lower end of the jack 32 is connected to the offset portion 28 of the abstract 16 by 105 a pin 33. Offsetting the portion 28 of the abstract produces a spring seat 34 and an expansive coil spring 35 may be inserted between the spring seat 34 and the jack heel 36. This spring is omitted when the 110 jack spring and touch regulator construction 37 is used. The details of the jack

spring and touch regulator 37 are shown, described and claimed in a companion application for a combination jack spring and touch regulator for upright piano actions, 5 filed September 9, 1919, Serial No. 322,733.

The damper spoon 38 extends upwardly from the rear end of the upper swing 25 and the equalizing damper construction 39 engages the damper spoon. The details of 10 the equalizing damper 39 are shown, described and claimed in my companion application for equalizing dampers for upright pianos, filed September 9, 1919, Serial No. 322,728.

15 The main action rail 40 supports the principal parts of the jack spring and touch regulator construction 37 and the equalizing damper construction 39. Brackets 41 extend forwardly from the rail 40 and support the regulating rail 42. The hammer butt 43 is connected to the flange 44 by a pin 45 and the flange 44 is connected to the main action rail 40. The back stop 46 is connected to the hammer butt 43 by a key- 20 stone tongue and groove joint 47, said joint being made with glue.

The back check 49 is not only a permanent part of the jack 32 but it presents a padded surface to contact with the regulating screw 48 and has a notched-in place in 30 the wood foundation to receive an elastic felt cushion, and then around this entire surface is drawn a buckskin cover 50 which is firmly glued to the wood portion of the 35 jack both at the front and at the back, and this felt cushion imparts elasticity and buoyancy and also acts like a shock absorber to the entire construction when the contact occurs with the regulating screw 48. Furthermore the padded surface on the rear of 40 the back check 49 has a permanent resting place against the covered surface 51 on the lower front side of the hammer butt 43 and also has a second support where the rear 45 52 of the top end of the jack rests against the lower padded portion 53 of the hammer butt 43, thereby giving to the jack a permanent double rest. The upper rear end 54 of the jack has a very sharp edge.

50 The surface 51 of the hammer butt 43 is cut curved and not flat and the felt is firmly glued to this curved surface so that the outer face of the felt presents a round side to the rear edge 54 of the jack. This gives 55 the jack 32 a double bearing against the hammer butt 43 and absolutely prevents friction and cutting and eliminates wear and secures permanency of parts. 56 is a damper carried by the damper lever; 57 is a piano wire, and 58 is the hammer arm carrying the hammer 59.

The lifter bar 60 is connected to the center of the swinging arm 30 by a pin 61 and the hammer rest rail 62 is connected to the 65 lifter bar 60 by a pin 63, and to the action

bracket 5 by an arm 62^a. It is to be understood that the hammer rest rail 62 extends the entire length of the action and that there is a lifter bar 60 at each end of the rail 62.

70

An abutment 64 extends forwardly from near the upper end of the action bracket 5 and a capstan screw 65 is screw-seated in the hammer rest rail 62 and rests upon a felt 66 upon the abutment 64. There 75 should be a capstan screw 8 and a capstan screw 65 at each end of the action.

The capstan screws 65 serve to adjust the hammer rest rail 62 to its proper normal position to regulate the normal striking distance of the hammer 59 from the wire 57. The capstan screws 65 and 8 are adjusted together to produce uniformity of touch and place proper tension upon the parts.

80 Referring to Fig. 3 which illustrates the action between the key and the abstract, and the means for adjusting relation between the two, 5 is the action bracket which rests at its lower end upon an adjustable foundation 5^a in the usual way and has an abutment 29 extending forwardly at a suitable distance above the extreme lower end. The arm 30 is connected to the bracket at its forward end by a pin 31 and at its rear end by screws 31^a seated in the end of the lower 95 flange rail 9. The lower swing 14 is pivoted at its rear end into the flange 12 which in turn is securely fastened to the flange rail 9 by means of the screw 13, its forward end being pivoted to the lower end of the abstract 16 by the pin 17. The arm 18 supports the regulating screw 19 which in turn rests at its lower end upon the rounded surface of the key 3 shown at 3^a.

100 In the usual form of construction the abstract 16 has its extreme lower end resting upon an adjustable screw seated into the end of the key 3 and receives the upward blow of the key; also the forward end of the swing 14 is pinned to the abstract 16 and 110 merely acts as a guide to hold the abstract in position which form of construction creates friction between the end of the abstract 16 and the capstan screw on which it rests. Again, regulating the usual form of 115 capstan screw is difficult as the operator must remove the tool used each time the screw is turned in order to test the action.

120 In my invention the abstract 16 does not rest upon the key, but as shown, is pivoted at its lower end to the swing, and the arm 18 of the swing 14 extends forwardly through the abstract and the regulating screw 19 rests upon the rounded surface 3^a of the key 3. This form of construction relieves the shock of the blow from the key on the end of the abstract by communicating it to the abstract through the regulating screw and the swing. It also reduces friction to the minimum as the felt pad on the 130

lower end of the regulating screw 19 rolls around the rounded portion 3^a of the key 3 instead of sliding on a flat surface as in the usual construction. Also the act of regulating by my improved construction is much more conveniently, quickly and easily accomplished owing to the fact that the regulating screw is very much more accessible and can be quickly and accurately adjusted without having to remove the regulating tool until the act of adjustment is completed.

Through the lifting motion of the pedal rod 67 when the soft pedal is operated the hammer rest rail 62 is moved upwardly 15 toward the piano wire on the arm 62^a. This movement carries the hammer 59 forwardly to the correct striking distance for the soft pedal action on the wire 57. This motion of the hammer rest rail 62 through the vertical 20 lifter bars 60 raises the rear ends of the flange rail swings 30 thereby raising the lower flange rail 9 thereby lifting the rear end of the lower action swing 14 which is fulcrumed upon the rear end of the key. This 25 last movement raises the abstract 16 thereby raising the jack 32 in proportion to the upward movement of the hammer butt 43, thereby keeping the upper end of the jack 32 at all times accurately adjusted to the 30 back stop 46 and the hammer butt 43.

The soft pedal rod 67 extends through the key-frame 1 and presses upwardly on the rail 62. The upper end face of the rod 67 has a projection 68 extending into the recess 35 in the rail 62 to hold the rod from slipping out of place. The rod 67 is operated by the soft pedal. The details of the soft pedal construction are shown, described and claimed in a companion application. Soft 40 pedals for upright pianos, filed Sept. 9, 1919, Serial No. 322729.

Thus I have produced an action for upright pianos, the essential or leading features of the action being a lower horizontal 45 swing, an upper horizontal swing, an abstract pivotally connecting the free ends of the lower and upper horizontal swings and extending above the upper swing, a jack pivotally connected to the upper end of the 50 abstract above the upper swing, a hammer butt pivotally mounted, a back stop rigidly connected to the hammer butt, a regulating screw mounted in the back stop, a back check extending from the jack and forming 55 a part of the jack and having a shock absorbing padded surface adapted to engage the regulating screw, the upper back corner of the jack being square and there being a curved pad upon the hammer butt to engage 60 the vertical face, and a rounded pad upon the hammer butt to engage the horizontal face and to engage the cushion padded back check.

The act of regulating the ordinary form 65 of upright action is one of extreme dif-

ficulty and a very vexing operation, often resulting in split, strained or broken parts, and owing to extreme complication as well as non-scientific assembling of parts the action seldom remains well regulated longer than a few months at a time. Reference to the drawing will show that in my action there are no wires to bend in the process of regulation and all regulating screws are on the outside in plain view and very accessible, and friction is reduced to the minimum in this action, and there can be but very small wearing of parts consequently a permanent as well as a stable regulation is obtained.

Blocking of hammers has always been one of the most annoying conditions in the upright action as well as one of the most difficult to prevent as there are many conditions which can cause it, and in my construction it is impossible to block the hammers.

My action is so constructed that all flange screws are easily accessible from the outside allowing the removal or replacement of any individual part while the action remains permanently in the piano.

Various changes may be made without departing from the spirit of my invention as claimed.

I claim:

1. In an action for upright pianos, a lower horizontal swing having a forwardly extending arm carrying an adjusting screw to rest upon the rear end of a key, an upper horizontal swing, an abstract pivotally connecting the free ends of the upper and lower horizontal swings and extending throughout its entire length in one continuous part, and a jack pivotally connected to the extreme upper end of the abstract above the upper swing.

2. In an action for upright pianos, a lower horizontal swing having a forwardly extending arm carrying an adjusting screw to rest upon the rear end of a key, an upper horizontal swing, an abstract pivotally connecting the free ends of the upper and lower horizontal swings and extending throughout its entire length in one continuous part, a jack pivotally connected to the extreme upper end of the abstract above the upper swing, a back stop extension forming a fixed part of the hammer butt, a regulating screw mounted through the back stop extension to contact with the back check, and a back check extending upwardly forwardly from the jack and forming a part of the jack and having a double padded surface adapted to engage the regulating screw, and a single padded rear surface to rest against the hammer butt, the upper back edge of the jack being square, a curved pad upon the hammer butt to engage the vertical face of the jack, and a rounded pad upon the hammer butt

to engage the padded rear surface of the back check to form a double bearing of the jack when at rest upon the hammer butt.

3. In an action for upright pianos, a hammer butt pivotally mounted, an abstract, a jack operatively mounted in the extreme upper end of the abstract, a back stop extension rigidly a fixed part of the hammer butt, a regulating screw mounted through 10 the back stop extension to contact with the back check, and a back check extending upwardly and forwardly from the jack and forming a part of the jack and having a double padded surface adapted to engage 15 the regulating screw, and a single padded rear surface to rest against the hammer butt, the upper back edge of the jack being square, and a curved pad upon the hammer butt to engage the vertical face of the jack

and a rounded pad upon the hammer butt 20 to engage the padded rear surface of the back check to form a double bearing of the jack when at rest upon the hammer butt.

4. In an action for upright pianos, the combination of an abstract spaced from the 25 key, a lower swing having its forward end pivoted to the lower end of the abstract, a regulating screw at the forward end of the lower swing for adjusting the abstract in relation to the key, said screw being engaged 30 by said key, whereby the shock of the key on the abstract is reduced and friction between the key and the abstract is substantially eliminated.

In testimony whereof I have signed my 35 name to this specification.

FRANK L. GEORGE.
